UNITED STATES PATENT OFFICE.

JOHN SCHALL, OF EVERGREEN PARK, ILLINOIS.

ROTATABLE SHOE-HEEL.

1,140,004.

Specification of Letters Patent.

Patented May 18, 1915.

Application filed November 12, 1914. Serial No. 871,658.

To all whom it may concern:

Be it known that I, JOHN SCHALL, citizen of the United States, residing at Evergreen Park, in the county of Cook and State of Illinois, have invented certain new and useful Improvements in Rotatable Shoe-Heels; and I do hereby declare the following to be a full, clear, and exact description of the invention, such as will enable others skilled in the art to which it appertains to make and use the same.

This invention relates to improvements in shoe heels and has for its object to provide a shoe heel having a tread member rotatable relative to the upper or fixed portion of the heel for the purpose of distributing the wear on the tread portion for maintaining the same substantially flat at all times.

The invention consists in the features of construction and combinations of parts hereinafter fully described and particularly claimed.

In the accompanying drawings illustrating the invention: Figure —1— is a perspective view of a shoe equipped with a heel embodying my invention. Fig. —2— is a central vertical longitudinal section through the heel portion of the shoe and the heel embodying my invention. Fig. —3— is a horizontal section on the line 3—3 of Fig. —2—. Fig. —4— is a detail perspective view showing the group of metallic parts embodied in the heel causing the same to operate in accordance with my invention.

My said heel comprises the part A which is fixed to the heel portion of the sole B of the shoe and the tread portion C which is rotatably mounted on the fixed portion A. The said tread portion C and the lower end of the fixed portion A are both relatively triangular in shape, the corners being widely rounded and the sides curved, as will more particularly appear from Fig. —3— so as to allow it to simulate in appearance the standard heel now generally employed. Mounted in recesses in the meeting faces of the portions A and C of the heel are substantially triangular plates D and E, each having a relatively large central opening and three relatively large perforations F arranged equi-

distantly from the axis of the central opening and equi-distantly from each other and in the corner portions are further provided with three smaller perforations G radially equi-distant from the axis of rotation and equi-distant from each other. The said plates are so mounted in the meeting faces of said parts A and C as to register with each other axially and peripherally as the edges of the meeting faces of the said portions register with each other. Each of said plates is secured in its recess by means of nails or brads H passing through the smaller perforations G and through the portion E and C respectively, of the heel, the brads securing the plate D passing also through the sole B of the shoe and being clenched upon the same in a well-known manner. Said portion A of the heel may be further secured to the sole B by short nails or brads in the usual and well-known manner.

Through the larger perforations in the plate E in the member C and into the body portion of said member I mount pins H having conical or rounded upper ends which project from the upper surface of the plate E and are adapted to engage in the perforations F of the plate D to hold said plates in register with each other and against relative rotation. Within the recesses containing said plates D and E I provide central recesses which receive the disks, which are circular, and are disposed concentric with the central openings in said members D and E and are of larger diameter than said openings. Disposed between said disks I and passing through the central openings in the plates D and E is a helical tension spring J secured at its respective ends to the disks I preferably by passing the ends of the spring through perforations in said disks and clenching them upon the other faces of the latter, it being understood, however, that the said ends of said spring may be rigidly secured to said disks in any other suitable manner. The said spring by its tension maintains the meeting faces of the parts A and C of the heel in close contact and normally maintains the projecting end portions of the pins H engaged in the perforations F

of the plate D thereby maintaining the peripheral edges of the portions A and C of the heel in register. The disks I are rotatable relatively to the plates D and E and by exerting a separating force upon said portions A and C of the heel to withdraw the pins H from engagement in the perforations of the plate D the same may be rotated through an arc of one hundred and twenty degrees whereupon the said pins will again register with and engage in the perforations F of the plate D, and in this position the peripheral edges of the parts A and C of the heel will also again register. By this means that corner of the heel disposed farthest rearwardly and subjected to the greatest wear may be turned so as to lie at one of the forward corners of the heel and thus successively each of said corners may be brought into position to be subjected to the greatest wear. Thus the heel is maintained at all times subject to substantially equal wear.

My invention is simple, easily applied and does not produce the so-called freak appearance of the shoe which would be objectionable commercially. The clenched ends of the brads securing the plate E to the part C of the heel may be covered by an additional layer of leather L, as shown in Figs. —1— and —2— to prevent said clenched ends being worn off and the plate E becoming loose therein.

In assembling the heel, the plates D and E, the spring K and the disks J are first assembled. By then turning said parts relatively to each other through an arc of about one hundred twenty degrees, the perforations for the brads G will be exposed and said brads inserted through all of said perforations. Then the plate D will be mounted in the upper member of the heel and said plates then turned so that their peripheral edges register with each other. The lower member of the heel, previously equipped with the pins H and provided with perforations for the passage of the brads G now carried by and projecting from the plate E, will be now moved to position, receiving said brads and causing the ends of the pins H to enter the openings in the plates E and D. The brads are then drawn up tight and clenched and the piece L mounted in place.

It will be noted that the outer diameter of the spring K is substantially the same as the diameter of the central openings in the plates D and E so that said spring constitutes the pivot about which said plates rotate relatively to each other. The device is thus rendered very light and simple in construction.

I claim as my invention:

1. In a shoe, a heel having a tread portion and a fixed portion rotatable relatively

to each other, said portions having respectively equal substantially polygonal meeting faces, and provided with interengaging formations adapted to maintain said faces in register with each other, the formations of at least one member corresponding in number and with the edges of the same and positioned relatively to the latter and the axis of rotation to cause said formations to register after each partial turn of said tread member through a given arc, and a spring for normally maintaining the meeting faces of said members in contact and said formations interengaged, said spring constituting the pivot about which said tread member is rotatable.

2. In a shoe, a substantially triangular heel having equal sides and angles and divided horizontally into two parts, plates mounted in recesses in the meeting faces of said parts and having registering central openings concentric with the axis of the heel, there being three sets of interfitting formations in said plates disposed equidistantly from said axis and from each other and arranged to interengage as the peripheral edges of the respective parts of the heel register, a spring for maintaining the meeting faces of said heel parts in contact with each other passing through said central openings in said plates and constituting the pivot about which the tread member is rotatable, and means rotatable relatively to said plates with which said spring is engaged at its ends.

3. In a shoe, a substantially triangular heel having equal sides and angles and divided horizontally into two parts, plates mounted in recesses in the meeting faces of said parts and having registering central openings concentric with the axis of the heel, there being three sets of interfitting formations in said plates disposed equidistantly from said axis and from each other and arranged to interengage as the peripheral edges of the respective parts of the heel register, a tension spring for maintaining the meeting faces of said heel parts in contact with each other passing through said central openings in said plates and constituting the pivot about which the tread member is rotatable, and means rotatable relatively to said plates with which said spring is engaged at its ends.

4. In a shoe, a heel divided horizontally into two parts, plates mounted in recesses in the meeting faces of said parts and having registering central openings concentric with the axis of the heel, there being interfitting formations in said plates disposed equidistantly from said axis and from each other and arranged to interengage as the parts of the heel are rotated relatively to each other through an arc equal to that separating con-

tiguous pairs of said formations, and a
spring for maintaining the meeting faces of
said heel parts in contact with each other
passing through said central openings in
5 said plates and constituting the pivot about
which the tread member is rotatable.

In testimony whereof I have signed my

name in presence of two subscribing wit-
nesses.

JOHN SCHALL.
